UNITED STATES PATENT OFFICE.

WILLIAM B. HAYDEN, OF NEW YORK, N. Y.

PROPELLER.

SPECIFICATION forming part of Letters Patent No. 794,010, dated July 4, 1905.

Application filed October 13, 1904. Serial No. 228,295.

To all whom it may concern:

Be it known that I, WILLIAM B. HAYDEN, a citizen of the United States, residing at New York, in the county of New York and State 5 of New York, have invented new and useful Improvements in Propellers, of which the following is a specification.

This invention relates to screw-propellers; and the object thereof is to so construct the 10 propeller as to enable the adjusting of the propeller-blades to a less or greater degree of pitch, whereby the position of the blades may be adapted to the particular degree of speed or power desired in the vessel propelled.

15 The invention further aims to provide a screw-propeller with a plurality of adjustable abutments adapted to engage the base of the blades to prevent the turning or loosening of the blades when in their set positions.

20 The invention further aims to provide a screw-propeller with means to readily ascertain whether the proper degree of pitch has been obtained when positioning the blades.

25 The invention further aims to construct a screw-propeller which shall be simple in its construction, strong, durable, and comparatively inexpensive to manufacture.

With the foregoing and further objects in view the invention consists of the novel combination and arrangement of parts hereinafter more specifically described, illustrated in the accompanying drawings, and particularly pointed out in the claims hereunto appended.

30 In describing the invention in detail reference is had to the accompanying drawings, forming a part of this specification, and wherein like reference characters denote corresponding parts throughout the several views, and in which—

40 Figure 1 is a sectional elevation of a screw-propeller constructed in accordance with this invention. Fig. 2 is a view showing one of the flattened portions of the hub. Fig. 3 is a view showing the base of the blade, and 45 Fig. 4 illustrates one of the blades in elevation.

Referring to the drawings by reference characters, 1 denotes the propeller-shaft, to which is fixed in any suitable manner the hub 2 for 50 the blades 3. The hub 2 at different points

on its periphery is flattened, as at 4. As shown, the periphery of the hub 2 is flattened at three points; but the number thereof can be increased or diminished, according to the number of blades 3 employed. The hub 2, 55 approximately centrally of each of the flattened portions 4, is provided with a protuberance 5, having a screw-threaded opening terminating in a screw-threaded recess in the hub. The screw-threaded opening of the protuberance and the recess in which said opening terminates forms a socket 6, the function of which will be hereinafter referred to. The hub 2 is further provided at each of the flattened portions 4 with a series of screw-threaded 60 recesses 7, four in number, said recesses disposed around the said protuberance and arranged with respect to each other substantially in the form of a square. The function of the recesses 7 will be hereinafter referred to. 65

70 Each of the blades 3 is curved at its outer end, as at 8, the function of which is to drive the water directly aft and prevent waste of power by centrifugal action. Each of the blades 3 at its inner end terminates in a base 9 of such diameter as to extend over the recesses 7, and centrally of the under face of the base 9 a screw-threaded connecting member 10 is provided, said member 10 being an integral part of the base 9 and adapted to engage 75 in one of the sockets 6 for detachably connecting the blade with the hub.

80 The adjustable abutments, which are adapted to engage the base of the blades 3 to prevent the turning or loosening of the blades 85 when in their set positions, consist of a series of headed jam-screws 11, operating in the recesses 7, there being four jam-screws 11 for each blade. The manner in which the screws operate to retain the blades in their set positions will be hereinafter referred to. 90

95 The means for ascertaining the positioning of the blades to the desired pitch consists in providing each of the flattened portions 4 of the hub 2 between a pair of the jam-screws 11 with a plurality of recesses 12, which form what may be termed a "pitch-scale," each recess indicating a different degree of pitch, and cooperating with said recesses 12 is a screw-threaded opening 13 in the base of each 100

of the blades. A removable pin 14 extends through the opening 13 and is adapted to engage in the recesses 12, so as to indicate that the proper degree of pitch has been obtained—that is to say, when the pin 14 finds a seat in one of the recesses 12 it will be indicated to the person adjusting the blade that a certain pitch has been obtained. The recesses 12 may be provided with suitable degree-marks, if desired.

The propeller is set up in the following manner: The connecting member 10 of each blade 3 is inserted in its respective socket 6; but before the connecting member is positioned the jam-screws 11 are placed in their respective recesses 7. As the setting up of all of the blades 3 is the same, the setting up of one only will be referred to. When the connecting member 10 is screwed into the socket 6, the blade is turned until the opening 13 in the base of the blade registers with one of the recesses 12, that recess which indicates the desired pitch for the blade. After the opening 13 registers with one of the recesses 12 the pin 14 is screwed home, so as to retain the blade at the pitch desired. When the connecting member 10 is inserted in the socket 6, it is not screwed therein until the base of the blade engages the protuberance 4; but the base extends slightly above said protuberance, or, in other words, does not engage the protuberance. As the desired pitch has been obtained in the manner as hereinbefore set forth, the jam-screws 11 are moved outwardly, so as to have their heads abut against the under face of the base, which action will be a somewhat pulling one—that is, pulling against the threads of the connecting member and the threads of the sockets 6 and such positioning of the jam-screws—that is to say, firmly abutting against the underneath face of the base of the blade—will prevent the turning or loosening of the blade, as the blade is what may be termed “fixedly secured” in position at the proper pitch desired. The heads of the jam-screws also act as bearings for the base of the blade. If it be desired to change the pitch of the blade, the jam-screws 11 are loosened, the pin 14 removed from the opening and the recess into which it extends, and the blade shifted until the opening 13 registers with another of the recesses 12. The blade is then secured in position in the same manner as heretofore pointed out.

It is thought the many advantages of a screw-propeller constructed in accordance with the foregoing description, taken in connection with the accompanying drawings, can be thoroughly understood, and it will, furthermore, be evident that changes, variations, and modifications can be resorted to without departing from the spirit of the invention or sacrificing any of its advantages, and I therefore do not wish to restrict myself to the details of construction as herein set forth, but

reserve the right to make such changes, variations, and modifications as come broadly within the scope of the protection prayed.

Having thus fully described my invention, what I claim as new, and desire to secure by Letters Patent, is—

1. A screw-propeller involving a hub, a plurality of adjustable blades carried by the hub, and a plurality of adjustable abutments interposed between the blades and the hub and independent of the blades for fixedly securing the blades in their adjusted positions. 75

2. A screw-propeller involving a hub, a plurality of blades adjustable to varying pitch, means for determining the pitch desired, and a plurality of adjustable abutments interposed between the blades and the hub for securing the blades to the pitch desired. 80

3. A screw-propeller involving a hub having a plurality of flattened portions, each of said flattened portions provided with a screw-threaded socket, a plurality of blades adjustable to varying pitch, each provided with a connecting member adapted to engage in the said sockets, and a plurality of adjustable abutments engaging in said flattened portions and abutting against the blades for securing the blades in position at the desired pitch. 85

4. A screw-propeller involving a hub having a plurality of flattened portions, each of said flattened portions provided with a screw-threaded socket, a plurality of blades adjustable to varying pitch, each provided with a connecting member adapted to engage in the said sockets, a plurality of adjustable abutments engaging in said flattened portions and abutting against the blades for securing the blades in position at the desired pitch, and means for determining the pitch desired. 90

5. A screw-propeller involving a plurality of blades adjustable to varying pitch, and a plurality of adjustable abutments independent of the blades for retaining said blades in the positions set. 100

6. A screw-propeller involving a plurality of blades adjustable to varying pitch and each having a curved extremity, and a plurality of adjustable abutments independent of the blades for retaining said blades in the positions set. 115

7. A screw-propeller involving a plurality of blades adjustable to varying pitch, and a plurality of jam-screws independent of and adapted to retain said blades in their adjusted positions. 120

8. A screw-propeller involving a plurality of blades adjustable to varying pitch and each provided with a curved extremity, and a plurality of jam-screws independent of and abutting against said blades for retaining them in their adjusted positions. 125

9. A screw-propeller involving a hub provided with a plurality of sockets, a plurality of adjustable blades having connecting members adapted to engage in said sockets, and a 130

plurality of jam-screws engaging in the hub, abutting against and independent of the blades for retaining them in their adjusted positions.

10. A screw-propeller involving a hub provided with a plurality of sockets, a plurality of adjustable blades having curved extremities and connecting members, said members adapted to engage in said sockets for connecting the blades with the hub, and a plurality of jam-screws engaging in the hub, abutting against and independent of the blades for retaining them in their adjusted positions.

11. A screw-propeller involving a hub provided with a plurality of sockets, a plurality of adjustable blades having curved extremities and connecting members, said members adapted to engage in said sockets for connecting the blades with the hub, a plurality of jam-screws engaging in the hub and abutting against the blades for retaining them in their adjusted positions, said hub provided with means for indicating the desired adjustment for the blades, each of said blades provided with an opening adapted to register with said means, and pins extending through said openings and engaging in said means for setting the blades at the desired adjustment.

in the hub for setting the blades to the desired adjustment. 25

12. A screw-propeller involving a hub provided with a plurality of sockets, a plurality of adjustable blades having curved extremities and connecting members, said members adapted to engage in said sockets for connecting the blades with the hub, a plurality of jam-screws engaging in the hub and abutting against the blades for retaining them in their adjusted positions, said hub provided with means for indicating the desired adjustment for the blades, each of said blades provided with an opening adapted to register with said means, and pins extending through said openings and engaging in said means for setting the blades at the desired adjustment. 30 35 40

In testimony whereof I have hereunto set my hand in presence of two subscribing witnesses.
